H. Hiken,

Brick Machine,

N° 85,197,

Patented Dec. 22, 1868.

HENRY AIKEN, OF PITTSBURG, PENNSYLVANIA.

Letters Patent No. 85,197, dated December 22, 1868.

IMPROVED BRICK-MACHINE.

The Schedule referred to in these Letters Patent and making part of the same.

To all whom it may concern:

Be it known that I, HENRY AIKEN, of Pittsburgh, in the county of Allegheny, and State of Pennsylvania, have invented new and useful Improvements in Brick-Machines; and I do hereby declare that the following is a full, clear, and exact description of the same, reference being had to the annexed drawings, making part of this specification, in which—

Figure 1 is a top view;
Figure 2 is an elevation;
Figures 3, 4, and 5 are separate parts of the machine;
Figure 8 is a bottom view;
Figure 9 is a perspective view of the plunger;
Figure 10 is a plan of a guide to the plunger;
Figures 6, 7, and 11 are views of the turtle of the pug-mill; and
Figure 12 shows the pressing-mechanism.

The same letters in all the figures indicate identical parts.

My improvements relate to that class of machines used for making pressed brick; and

My invention consists in so constructing the machine as to make pressed bricks at one operation from tempered clay. The character of the new combinations used in the accomplishment of this purpose will appear from the following specification and claims.

The following description, in connection with the drawings, will enable persons skilled in the art to manufacture and operate my improved machine.

The power may be applied to the pulley A, on the main driving-shaft A¹, and is communicated, by means of the bevel-pinion A², to the bevelled master-wheel B.

The master-wheel is placed on a vertical shaft, B², having its step on the frame of the machine.

The master-wheel is attached to a cylindrical body, in the bottom of which is cut a heart-formed groove, to form a cam for operating part of the mechanism, to be hereinafter described.

On the shaft B² is also a pinion, B³, which will also be more fully described.

On the upper end of the shaft is a spur-pinion, B⁴, which drives the spur-wheel C, on the top of the pug-mill shaft.

The pug-mill is supported upon the bed-plate E, and upon its shaft is a series of paddles to cut the clay, and, by their screw-formed position, to drive it constantly downward.

I do not claim that there is anything new about this portion of the mechanism.

The turtle on the lower end of the pug-mill shaft is, however, of a peculiar and novel form. It is constructed with three wings, as shown in figs. 6, 7, and 11, and its object is to force the clay into the moulds, and at the same time smooth it off. This is accomplished by reason of the peculiar form of the parts of the turtle, as clearly shown in the drawings.

The turtle is set on the lower end of the pug-mill

shaft, and the wings extend to and radiate from the centre, so that the arms have a sweeping-operation over the face of the clay, in whatever position the turtle may be placed. The shaft does not turn upon a step, as is usually the case, but is suspended upon bearings, so that there is an entirely uninterrupted space between the mould-wheel and the turtle. The turtle is set closely over the moulds, and its entire lower surface is upon the same horizontal plane.

The moulds D¹ are in the mould-wheel D. They are lined with steel, and formed so as to make three or more bricks at one operation. The clay, properly tempered in the pug-mill, is fed down by the paddles, and forced by the turtle into the open mould as it passes under the pug-mill.

To accomplish this, it is necessary to give an intermittent revolution to the mould-wheel. This is effected by means of the pinion B³, working into cogs on the periphery of the mould-wheel.

The pinion has the teeth stripped from nearly one-half its circumference, so that it only gives motion to the mould-wheel, while the cogs in the pinion mesh with the gearing upon the rim of the mould-wheel.

The gearing is so proportioned that the teeth in the pinion shall suffice to engage the teeth of the mould-wheel only during so long a time as may suffice to bring the moulds successively under the pug-mill, where they will remain stationary during the remainder of the revolution of the pinion, thus affording ample time for the turtle to fill the moulds and smooth off the upper surface of the clay.

When the teeth of the pinion first begin to engage those of the wheel D, the strain will be upon a single tooth in each wheel.

In order to sustain this duty, the corresponding teeth thus encountering b and d are made of about double the strength of the other cogs.

A plate is fastened upon the lower side of the pinion B³, and a segment projects around all that portion of the circumference of the pinion that has been stripped, and a corresponding recess is put in the edge of the mould-wheel at d, (figs. 1 and 2,) to receive this projecting segmental flange.

The flange is so arranged, in relation to the wheel, with its recesses d', that during all that part of the revolution in which the teeth are not in gear, the flange shall prevent any motion of the mould-wheel, which is essential to the operation of both the filling and pressing-mechanism.

The bottom of the moulds is formed by a plunger, D², which is subdivided into as many heads as there are bricks to be formed in the mould. The tops of the head of the plunger are covered by steel plates, as clearly shown in fig. 9, and by the dark portion of the plunger shown in fig. 10.

The object of this construction is to enable the working-surfaces to be removed, by taking off these plates

and spreading them as soon as they become worn, so as to always maintain a tight fit. The wear, by constantly grinding upon these surfaces of gritty particles, is very rapid, and this mode of providing against it cheaply is regarded as important.

These plates have heretofore been used, but their edges were flush with the faces of the plunger. By making them wider than the plunger, as shown, it is provided that space shall be left between the faces of the plunger and those of the mould, for any particles of clay that may pass by the edges of the plate to fall out of the mould, without causing increased friction and consequent wear of the parts.

This diminution of the size of the plungers also enables me to use the adjustable guide-plates of the plunger D⁴, to be elsewhere explained.

As the plates alone come in contact with the edges of the moulds, the wear is upon them alone, and, consequently, as they are worn away, it is only necessary to remove the plate, and to spread them, to make the fit perfect. The diminution in the thickness of the plates, by thus spreading, may easily be compensated by placing sheets of paper between them and the plunger-head.

When the moulds have been filled, they are carried forward with the revolution of the wheel, and brought under the edge of a knife, E¹, set in the bed-plate E, and so formed, as shown in figs. 1, 3, and 4, as to shave off the top of the brick, leaving a smooth surface.

In front of the knife there is an inclined, smooth surface, e', which, inclining downward, serves to compress the clay more closely into the mould before it is subjected to the shaving action of the knife. There is nothing peculiar in the form of the knife itself. The knife is not attached to the bed-plate directly, but is fastened into a block, which is set into the bed-plate, and held in place by set-screws.

The inclined face e' is cast in the block, and is intended as a more convenient and cheaper manner of producing the same effect as is produced by the inclined plate shown in Sword and Tiffany's and Sword's patents for the same purpose.

The upper bed-plate, E, is supported by rods, passing through the lower bed-plate, E³. The mould-wheel is placed between these bed-plates, running in a groove in the lower one, and the lower bed-plate is sustained upon the main frame of the machine. The upper bed-plate is supported on the rods between the two nuts on each rod, one above and the other below the plate, so that as the plate wears, as it does rapidly, it may be set down by turning the nuts.

The bricks, after being shaved by the knife, are carried with the revolution of the mould-wheel until they arrive at a point under the opening E², in the bed-plate E. Here the wheel again is stopped until the brick is subjected to the action of the mechanism which presses it.

The pressing-mechanism is arranged as follows:

F is the press-plate, which is a bar fastened at one end to the head of the shaft of the mould-wheel F³, and at the other to a vertical rod, F⁴, which passes down through a hole in the lower bed-plate, and is fastened to a sill-piece, F⁴, fig. 8, which in its turn is attached by one end to the rod F³, and by the other to the lower end of the mould-wheel shaft, so that the parts F F³ F⁴, with the shaft of the mould-wheel, form a frame to sustain the pressure independently of any other parts of the mechanism.

The brick is pressed between the plunger D² and a pressure-plate, F¹, which is fitted into the hole E² in the upper bed-plate. This plate F¹ is attached by a stem to the middle of the press-plate F.

The plungers are forced up by means of a toggle-joint, G, which is placed between the bottom bar, F⁴, on which one end is jointed, and the plungers.

The upper arm of the toggle-joint works through a supporting-guide, attached to the underside of the lower bed-plate, E¹, and I form it with a head, to act against the lower face of the plunger.

The toggle-joint is operated by two parallel rods, H, fastened at its elbow. The parallel rods are extended so as to pass beyond the shaft B², and are properly fastened at the end.

A roller, H', on a wrist-pin, is attached to the parallel rods, and received in a heart-formed recessed cam, B', in the wheel B, as already described.

The toggle-joint is operated up and down, once at each revolution of the wheel B, and the groove is so formed that the press shall only be in motion when the mould-wheel is stationary.

The plungers work between four guides, D⁴, fig. 10, placed at the corners. These guides are attached to the lower face of the mould-wheel by set-screws, passing through slotted openings in the guides, so that they may be set up as they wear.

Set-screws or headed bolts, not shown, are screwed into the lower edges of the moulds, in such position that the heads, catching against shoulders formed in the plungers, shall hold them when down, and prevent their dropping out.

When the bricks have thus been pressed, they pass on with the revolution of the wheel until the roller d² in the bottom of the plunger bears against the upper face of the incline D³, which is fastened to the lower bed-plate.

As the roller passes along the inclined face of the plate D³, the plunger is forced up, and the brick is carried on the upper face of the wheel, still resting on the head of the plunger, until it reaches the oscillating cross-head L¹, which, traversing the face of the mould-wheel over the moulds successively, is operated as follows:

A bent lever, I, is pivoted at the elbow upon a wrist-pin, projecting from the lower cross-piece of the main frame.

The short arm of this bell-crank lever is slotted to receive a wrist-pin, I¹, attached to the parallel rods or straps H, below the roller H¹.

The long arm of the bell-crank lever is pivoted to the arm I², and this is in like manner fastened to the yoke I³.

This yoke is pivoted to the oscillating arms K K, which are pivoted to the frame O.

The arms are connected by a rod, at their ends, to the straps L, which give motion to the sliding cross-head L¹, placed upon the parallel rods M, attached to the upper bed-plate, and which, passing through eyes in the cross-head L¹, guide it across the face of the mould-wheel.

As the mechanism operating the cross-head is attached to the rods H H, it follows that the cross-head will only be in motion while the wheel is stationary, so that as the inclined plate forces up the bricks, they are raised to the surface between the straps L L, and in position to be swept off by the cross-head.

When thus swept off they are carried upon the bridge-plate P, which is bolted to the frame O, and extended close up to the edge of the mould-wheel, and from there they are carried over to the endless apron N, turning upon rollers N' on the frame O, from which they are removed to the sheds, where they may be immediately haked up to dry, being so hard as not to require to be placed on the drying-floor.

When the bricks have been thus swept off, as the mould-wheel moves forward again, the form of the inclined plate D³ allows the plungers to fall by their own gravity before passing under the pug-mill to be again filled.

The cross-head L¹ is made in the form of a trough, and is used for oiling the moulds. A brush is attached

to this oil-box, which sweeps the top of the moulds, and being connected with the oil-reservoirs, at the same time oils them.

It will be observed that the pug-mill is in continuous operation, but the mould-wheel only in intermittent motion, it being at rest while the operations of filling the moulds, pressing the bricks, and sweeping off those raised to the surface of the wheel are going on, simultaneously upon different parts of the wheel.

What I claim as my invention, and desire to secure by Letters Patent, is—

1. In combination with a pinion, B³, having teeth upon only part of its periphery, and the mould-wheel D, the segmental flange b³ and the recesses d³, arranged to operate substantially as and for the purpose set forth.

2. The spur-pinion B³ and mould-wheel D, having cogs, respectively, as set forth, when the respective cogs b and d are constructed with a pitch uniform with the other cogs of the respective wheels, and a space is formed in front of the tooth d, and between it and the next cog in the series, to receive said teeth b, substantially as set forth, and shown in the drawings.

3. The knife E¹, when attached to a cast block inserted in the upper plate E, said block having also an inclined lip, e¹, arranged in relation to the mould-wheel and the knife, substantially as and for the purpose set forth.

4. In combination with the bed-plate E and frame X of the brick-machine, the auxiliary frame F, F³, F¹, and F², to which the press and press-plate are so attached that the strain of the press shall be sustained upon said auxiliary frame, and not by the main frame or bed-plate, substantially as herein described.

5. The combination of the toggle-joint press, and the frame formed of the parts F, F³, and F¹, and the shaft of the mould-wheel, substantially as set forth.

6. The combination of two bed-plates enclosing the mould-wheel, and having the upper one supported by rods and double nuts, so as to be adjustable, substantially as and for the purpose set forth.

7. The combination of the sweep L¹, and rods and levers L, K, I³, I², and I, and the cam B¹, which operates the same, substantially as set forth.

8. The upper bed-plate, with openings for knife E¹ and press-plate F¹, as set forth.

9. In combination with the plungers, adjustable guides D⁴, arranged in relation thereto, substantially as set forth.

In testimony whereof, I have signed my name to this specification, in the presence of two subscribing witnesses.

HENRY AIKEN.

Witnesses:

JOHN E. LITTLETON,
JOHN McCOY.
